UNITED STATES PATENT OFFICE.

CHARLES FREDERICK RANDALL, OF DENVER, COLORADO.

TROLLEY ADJUSTING AND REGULATING DEVICE.

SPECIFICATION forming part of Letters Patent No. 573,535, dated December 22, 1896.

Application filed March 31, 1896. Serial No. 585,598. (No model.)

To all whom it may concern:

Be it known that I, CHARLES FREDERICK RANDALL, a citizen of the United States of America, residing at Denver, in the county 5 of Arapahoe and State of Colorado, have invented certain new and useful Improvements in Trolley Adjusting and Regulating Devices; and I do declare the following to be a full, clear, and exact description of the invention, 10 such as will enable others skilled in the art to which it appertains to make and use the same, reference being had to the accompanying drawings, and to the figures of reference marked thereon, which form a part of this 15 specification.

My invention relates to improvements in devices for automatically regulating the position of the trolley on electric-motor cars.

The mechanism has a threefold function, 20 namely: the taking up and paying out of the slack of the rope attached to the trolley-pole, the catching of the trolley-pole when it flies off the overhead wire, and, lastly, the pulling down of the trolley after it has been caught. 25 The construction set forth in this application may be considered an improvement on the construction covered by my previous application, Serial No. 538,011, filed February 11, 1895. The said previous application 30 braces mechanism for taking up the slack in the rope and catching the trolley when it flies off the wire. The new feature of this application comprises the pull-down mechanism and its connection with the catching mechanism, whereby the pulling down of the trolley 35 is automatically accomplished.

Another feature of the invention consists of a guide for the trolley-rope.

Having thus briefly outlined the function 40 of the invention and its novel features, I will now proceed to describe the same in detail, reference being made to the accompanying drawings, in which is illustrated an embodiment thereof.

In the drawings, Figure 1 is a vertical longitudinal section taken through the trolley-adjusting mechanism. Fig. 2 is a horizontal section taken on the line $x-x$, Fig. 1. Fig. 3 is a fragmentary vertical section taken on the 45 line $y-y$, Fig. 2. Fig. 4 is a top view of the trolley-guide attached to the hood of the car. 50

Fig. 5 is a top view of the construction shown in Fig. 1 with the top plate removed.

Similar reference-characters indicate corresponding parts in the views.

Let the numerals 5 and 6 designate two tubes or hollow casings. To the top of these tubes is applied a plate 7, having a vertical or depending flange 7^a on its outer edge. The lower extremities of the tubes engage a 60 base-plate 8, so constructed as to retain the tubes securely in place. This base-plate is provided with outwardly-projecting apertured lugs 8^a, which afford means for fastening the device to the platform of the car. 65

The top and bottom plates are connected by vertical rods 9, located between the tubes, which are separated by a narrow space 10. These rods are fastened by nuts. Hence by means of the rods and the top and bottom 70 plates the two tubes are securely connected and maintained in operative relation. Within the tube 5 is located the weight 12, having guide-grooves formed in two opposite sides. One of these grooves engages a stationary 75 tongue 5^a, formed on the inside of the tube, while the other engages a ratchet-bar 13, having a limited vertical movement. The movement of the ratchet-bar is controlled by small bolts 14, screwed into the ratchet-bar and 80 passing through short slots 5^c, formed in the casing 5.

A block 15, carrying two pulleys 16, is attached to the weight 12 by means of a pin 17. The lower extremity of this pin is enlarged, 85 forming a shoulder, against which bears a coil-spring 18, which surrounds the pin. The upper extremity of this spring engages a shoulder formed on the weight and surrounding the aperture formed in the top of the 90 weight through which this pin passes.

It will be observed that the weight is recessed to receive the enlarged lower extremity of the pin, said recess being reduced at the top, where it is only large enough to allow the 95 pin to move easily therein. The enlarged part of the recess allows the enlarged extremity of the pin a free vertical movement. To the lower extremity of the pin 17 is movably attached a pawl 19, located in a recess 100 20, formed in the weight to one side of the recess in which the pin is located. This pawl

normally occupies an inclined position, its outer extremity being in close proximity to the teeth of the ratchet-bar 13.

Located in the top of the tube 5 and supported on the plate 7 are two pulleys 21 and 22, while a pulley 23 is located in the top of the tube 6 and also attached to the plate 7.

The trolley-rope 34 is connected with the trolley-pole (not shown) at one extremity, passes through an aperture in the plate 7, thence downward around one of the pulleys 16, thence upward and over the pulley 21, thence downward around the other pulley 16, and thence upward over the pulley 22, thence out of the tube 5 into the tube 6 to engagement with the pulley 23, its lower extremity being attached to the large weight 24, located in the tube 6. To this weight is attached a handle 24^a, projecting through a vertical slot 20 formed in the casing of the tube 6 and accessible from the outside of the tube. Between the tubes 5 and 6 is located a horizontal plate 25, supported by sleeves 36 and 37, which surround the vertical rods 9, which pass 25 through apertures formed in the plate 25, said apertures being only large enough to allow the rods to slip through them. The sleeves 36 are located above the plate 25, while the sleeves 37 are located below said 30 plates. The adjacent extremities of these two sets of sleeves form, in effect, shoulders which maintain the plate securely in place. The plate 25 is apertured to receive a dog 27, which is centrally pivoted on the plate, and normally occupies an inclined position, whereby its upper extremity protrudes through an aperture formed in the casing 5, while its lower extremity projects through an aperture formed in the casing 6. The lower 35 extremity 27^a of this dog is beveled and provided with a projection adapted to enter a recess 24^c, formed in the weight 24. The upper extremity 27^b of the dog is curved and normally occupies a position just above the 40 top of the movable ratchet-bar 13. The dog 27 is held in its normal position by a suitable spring 28.

The operation of the mechanism as thus far described, assuming that the parts occupy 50 the relative positions shown in Fig. 1, is as follows: As soon as the trolley slips off the wire the recoil of the spring-pole gives a sudden upward jerk on the rope 34, forcing the enlarged lower extremity of the pin 17 against the spring 18, which yields sufficiently to throw the pawl 19 into the teeth of the ratchet-bar 13, which will be immediately raised sufficiently to operate the dog 27 and release the weight 24, which will drop downward in the 55 tube 6 and pull the trolley downward sufficiently to prevent its coming in contact with overhead obstructions. The gravity of the weight 24 is so regulated as to cause it to perform the function stated.

65 It will be observed that the stop-bolts 14 prevent the ratchet-bar from rising farther than may be necessary to operate the dog 27

and release the weight 24. Hence as soon as the weight 24 is released the weight 12 is locked against further upward movement 70 and the downwardly-moving weight 24 is free to act on the trolley through the connections described.

As soon as the trolley has again been placed on the wire the motorman grasps the protruding handle 24^a of the weight 24 and raises the weight to its normal position, when the lower extremity of the dog 27 again enters the recess 24^c and supports the weight until the trolley again slips off the wire. 80

As long as the trolley is on the wire the weight 12 gradually rises and falls within the tube 5, taking up the slack and paying out the rope according to the variations in the height of the trolley in different parts of the 85 system.

The device illustrated in Fig. 4 comprises a bracket 29 and a curved spring 30, having one extremity made fast to the bracket which is secured to the hood 31 of the car. The bracket 90 is hollowed out and forms, in connection with the spring, a circular passage, through which the trolley-rope passes and within whose limits it is normally confined. The extremity of the spring normally engages the bracket and 95 closes the circular passage-way. The spring, however, is sufficiently yielding to allow the trolley-rope to be thrown in and out of position at the will of the person in charge of the car. The free extremity of the spring 30 curves outward, as shown at 30^a, forming a sort of hook, against which the rope is drawn when it is desired to slip it into the guideway formed by the bracket and spring. 100

Though I have shown and described two 105 distinct tubes 5 and 6, suitably connected, I do not limit the invention to this specific construction, as I am aware that any casing adapted to contain the two weights and arranged to support the movable ratchet-bar 110 and the dog 27 in operative relation with the other parts may be employed without departing from the spirit of the invention.

Having thus described my invention, what I claim is— 115

1. In a device of the character described, the combination of a casing comprising two compartments 5 and 6, the compartment 5 having a weight provided with a yielding pin, a block and pulley attached to said pin, the 120 pulley being engaged by the trolley-rope, a pawl attached to the yielding pin, a ratchet-bar having a limited movement within the compartment 5, a pulley supported in the upper part of the compartment 5, and over which 125 the trolley-rope passes, another pulley supported in the upper part of the compartment 6 and also engaged by the trolley-rope, a weight located in the compartment 6, and to which the trolley-rope is attached, and a 130 spring-held dog suitably supported and having one extremity normally projecting into the path of the ratchet-bar, while the other extremity engages and supports the weight

in the compartment 6, substantially as described.

2. The combination of a casing comprising two compartments, 5 and 6: two weights, one located in each compartment, a yielding pin attached to the weight in compartment 5 and having a limited vertical movement, a pawl pivoted on said pin and a spring-held dog suitably supported and having one extremity normally projecting into the path of the ratchet-bar, and the other extremity engaging and supporting the weight in compartment 6, the trolley-rope being connected with the weights in the two compartments, substantially as described, and for the purpose set forth.

3. The combination with two weights, 12

and 24, of a receptacle adapted to contain said weights, a yielding pin attached to the weight 12, a pawl pivoted on the pin, a vertically-movable ratchet-bar located in suitable proximity to the weight 12, a spring-held dog suitably supported and having one extremity normally projecting into the path of the ratchet-bar, while the other extremity engages and supports the weight 24, and a suitable trolley-rope connected with the weights, substantially as described. 20 25

In testimony whereof I affix my signature in the presence of two witnesses.

CHARLES FREDERICK RANDALL.
